PHOTOGRAPHIC EASEL

Benjamin B. Mahler, Newark, N. J.

Application May 17, 1949, Serial No. 93,731

3 Claims. (Cl. 88—24)

1

This invention relates to easels for photographic purposes, especially for use in making photographic enlargements, and more particularly to an easel of the adjustable type.

Commercially used photographic easels are designed to hold sensitized paper flat during the exposure and to mask a border of a paper in order to form a border on the completed print.

One known form of photographic easel embodies a frame which accommodates paper of one size only. Consequently, this type of easel is needed in as many different sizes, that is, in such a number, as there are different paper sizes used by the same darkroom worker. It will be understood that the purchase of a number of complete, self-contained easels is uneconomical.

Suggestions have, therefore, been made to provide an easel which can be adjusted to any size of paper and does not have to be replaced by another easel whenever a different size of paper is to be used. A common form of this type of easel uses slidably arranged borders. However, this construction is complicated and requires that a bright light be turned on in the darkroom to make it possible for the borders to be adjusted correctly. Apart from this, the adjustment is a rather delicate job and takes too much time.

It has also been suggested to provide an easel having a backing, a holding frame connected thereto, and a number of so-called leaves clamped between the backing and the holding frame, each of the leaves having an opening of a different size. The print paper to be used is placed within the frame and held between two adjoining leaves. The construction according to this suggestion is also complicated in requiring means to connect the holding frame to the backing, means to hingedly hold the leaves, and means to hold the leaves against relative movement.

The prime object of my invention is to generally improve easels of the type referred to. The invention aims at an easel which will not have the disadvantages of the prior art constructions, but instead will embody all of the commercially desired advantages, as simpleness in construction, low cost in manufacture, easy and quick handling in use, and production of prints having perfectly straight borders.

More specifically, important objects of my invention center about the provision of an easel which can readily be assembled and disassembled and which can be adjusted to any of the standard sizes of photographic paper in a matter of seconds and in complete darkness besides. Another more specific object of my present inven-

2

tion is to provide an easel which makes it possible to use paper which may be of any shape as long as two adjacent sides of the sheet are cut at a right angle, yet which ensures, as mentioned above, the formation of definitely straight borders. Still another object of my invention is to provide an easel which is sturdy in structure.

To the accomplishment of the foregoing and such other objects as may hereinafter appear, 10 my invention consists in the elements of a photographic easel and their relation one to the other as hereinafter are more particularly described in the specification and sought to be defined in the claims. The specification is accompanied by drawings in which:

Fig. 1 is a perspective view of a photographer's easel embodying features of my invention, with some parts of the assembly in separated condition, showing the easel in its normal or operative position;

Fig. 2 is a perspective view of a disassembled part of the device of Fig. 1;

Fig. 3 shows the easel of Fig. 1 and is explanatory of the insertion of sensitized paper in the 25 easel;

Fig. 4 is a perspective view of an easel using one of the parts of the device of Fig. 1 in combination with an exchanged part, again showing the insertion of sensitized paper;

Fig. 5 is a perspective view of a modified easel;

Fig. 6 is a fragmentary end elevation of the easel of Fig. 5 drawn to enlarged scale and showing one of the parts in an elevated position to permit insertion of sensitized paper;

Fig. 7 is similar to Fig. 6, but showing the same part in a different position;

Fig. 8 is a perspective view of another modification of the easel according to my invention;

Fig. 9 is an enlarged section taken approximately in the plane of the line 9—9 of Fig. 8; and

Fig. 10 is a fragmentary perspective view of a disassembled part of the device of Figs. 8 and 9.

Referring now to the drawings in greater detail but having first reference to Figs. 1 to 3, 10 designates a base made of plastic material. The base or at least its top surface 12 is of white color to permit focusing. Secured to the base on its side 14 are three threaded studs 16. A frame generally designated 18 is removably placed over the base. The frame is an oblong structure, the border 20 being of identical width all-round and enclosing an opening 22. The frame is provided along two adjacent sides with flanges preferably formed by bending the corresponding border portions downwardly approximately at right angles,

the flange 24, which coincides with the side 14 of the base, being of a configuration to form two horizontally extending slots 26, and the flange 28 being plain. Both slots 26 open in the same direction and form seatings for two of the studs 16. The frame is also provided with a finger grip 30.

Thus, one form of my invention comprises a base and frame as shown in Figs. 1 to 3. While the base may be made of wood or metal as well as plastics, whereby a white top may be provided by using a sheet of white plastic material or simply white paint, the frame, according to an important feature of the invention, is made of spring steel or any other resilient metal or metal alloy. The frame 18, shown in Fig. 2 in disassembled condition, is placed over the base 10 by putting the frame on the base from the top so that the studs 16, indicated in dash-dotted lines in Fig. 2, appear in front of the mouths 32 of the slots 26, and by sliding the frame in the direction of the arrow indicated in Fig. 1 until two of the three studs are seated in the two slots and the flange 28 lies against the contiguous side of the base block. When fitted over the base, the frame is in operative position and will be retained in this position by tightening the knurled nuts 34 (see Fig. 3).

To use my easel for holding print papers, use is made of the pivotal support of the frame. It will be understood that the frame is adapted to bend in the region between the respective border portion and the flange 24. When raised to the position shown in Fig. 3, the frame tends to swing back due to its springiness. The flange 24 is bent downwardly preferably at an angle slightly less than 90° with the border 20 to increase the spring pressure. By using the grip 30, the frame is swung to the position of Fig. 3, and while in this position, a sheet 36 of print paper is edgewise inserted between the frame and base, as is clearly shown in Fig. 3, until the two adjacent sides of the paper sheet, which move toward the flanges 24 and 28, hit the flanges. Then, by releasing the grip 30, the frame 18 swings back to the position shown in Fig. 1 to hold the paper flat and securely to the base.

The paper removing action is similarly accomplished as the new paper positioning action by swinging the frame to an elevated position and by allowing the frame afterwards to swing back due to the inherent springy properties of the frame. Attention is called to the fact that the flange 28 is relieved at 38 not only to make the forming operation of the flanges 24 and 28 easier, but also to make the frame more easily bendable along the line 40.

It will be obvious that my easel requires only two adjacent sides of the print paper to be cut at a right angle. The paper may otherwise be of any shape. The paper is inserted so that those two adjacent sides move toward the flanges 24 and 28 which form abutments and locate the paper adequately.

According to my invention, I use a single base and a number of different sizes of frames, the base and the frames forming a unit to be used for all standard sizes of print paper. It will be clear that upon removing of one size of frame from its connection with the base, the base will be ready to be united with a different frame. It is possible to provide a single base to be used with as many frames as are needed to accommodate all standard sizes of paper, or two or three different bases each being adapted for the use of a part of the total number of sizes. My easel, what-

ever size of frame is used with the base, ensures perfectly straight borders. The base need be only slightly larger than the largest size of photographic paper to be used with that base.

Referring to Fig. 4, the easel selected for illustration in this view consists of the same base 10 and a frame 42. The frame consists of a border 20' provided with a finger grip 30' and two depending flanges 28' and 44. While the flange 28' is similar to the flange 28 (Figs. 1 to 3), the flange 43 is designed to form three horizontally extending slots 26' to receive all of the three studs 16. The frame 42 is similarly brought in place and similarly tightened to the base as was previously described. For its swinging or pivotal movement, the frame 42 depends on its support on the three studs 16.

To accommodate the paper 36', which is larger than the sheet 36 (Fig. 3), a correspondingly larger frame, namely, frame 42, is used with the base 10; the mounting of the frame on the base, the function and operation of the frame being, however, exactly the same as explained above.

In Figs. 5, 6 and 7, the easel shown comprises 25 a C-shaped metal base 44 and a rigid frame 46. The frame essentially comprises a border 48 a flange 50 and two flanges 52, all of the flanges being directed downwardly, and the latter two flanges being shaped to form horizontally extending slots 54. The base supports two oppositely arranged pivot pins 56 received by the slots 54 for swinging movement of the frame. A spring 58 is tensionally held between the base at 60 and the frame at 62.

When placed over its base, the frame 46 is held down, and when raised to the position shown in Fig. 6, the spring urges the frame back against the base. If the frame is raised to the position shown in Fig. 7 and the spring coincides with the line passing through 60 and 62, the spring force will exert an endwise pull but no longer tend to turn the frame. While in the position of Fig. 7, it is possible to insert papers in the easel without holding the frame by hand. If the frame is turned into a position (not shown) beyond that of Fig. 7, the spring will tend to move the frame in opposite direction.

To replace the frame 46 by a similarly but differently sized frame, the spring is taken off, the old frame slipped off so as to free the pivot pins 56, the new frame slid into position, and the spring again fastened.

In inserting the paper in the easel of Fig. 5, the paper is moved until it touches the flange 50 and the left flange 52. Again, papers having just two adjacent sides at a right angle yield pictures with all-around straight borders.

In the particular constructions shown in Figs. 1 to 7, frames are used one or two flanges of which 60 are shaped to form horizontally extending slots. However, it will be understood that the horizontal extension of the slots is not essential. The slots may just as well extend differently, but care must be taken, according to my invention, that the flanges of the frame do not interfere while the frame is brought in place, and that the frame flanges form the desired abutments when the studs are seated in the slots.

The form of my invention shown in Figs. 8 and 70 9 comprises substantially a base 64, a frame-holder 66, a rigid frame 68, and a wedge strap 70. The frame holder is pivoted on the base at 72. The frame holder comprises a lower section 74 and an upper section 76, the lengthwise extending space 75 between these sections receiving the border por-

tion 78 of the frame and the wedge strap. The frame is brought in place by moving same edge-wise in the direction of the arrow shown in Fig. 8 with the border portion 78 moving first. While the frame is brought in place, the wedge strap 70 is in the position shown in Figs. 8 and 9 whereby the individual wedges 80 project into the apertures 82 provided in the upper section 76, thus leaving an idle space 84 between the wedge strap and the frame 68. Once the frame has been inserted, the wedge strap is pushed to the right, thereby wedging itself into the idle space and locking the frame in position. Provision can as well be made to arrange the wedge strap between the frame and the lower frame holder section.

It will be clear that with the base 64 and frame holder 66, as shown in Figs. 8 and 9, different sizes of frames may be used. It will also be clear that the wedge strap has to be moved into the opposite direction to allow a frame to be taken out and to be replaced by a frame of a different size.

It should be understood that the frames to be used with the easel of Figs. 8 and 9 are provided with one flange only, as clearly shown in Fig. 10. This flange is designated 86 and corresponds to the flange 28 shown in Figs. 1 to 3. The adjacent flange needed to properly locate papers is provided on the frame holder 66 and is designated 88.

From the foregoing, it will be seen that all of the parts, which according to this invention form an individual unit of easel, are simple in structure, inexpensive to manufacture, and easy and quick to assemble and disassemble. The assembled easel will be easy to operate and will be reliable in function.

It is believed that the construction and operation, as well as the many advantages of my improved easel, will be apparent from the foregoing detailed description thereof. It will also be apparent that while I have shown and described my invention in preferred forms, many changes and modifications may be made in the structures disclosed without departing from the spirit of the invention.

I claim:

1. In a photographic easel, a base having a paper-supporting top, and sides, a paper-holding apertured frame, at least two studs spacedly projecting from one of said sides, said studs being arranged in a straight line and being

threaded at their free ends, and matingly threaded nuts to fit the stud threads, said frame being made of resilient material and being placed over the base to fit around the studs for being releasably tightened to the base by means of said nuts, the frame having on two adjacent sides downwardly directed flanges to form abutments for properly locating the paper to be supported by the base and to be held by the frame, the resilience of the frame material urging the frame, upon its bending about a line parallel to said line, to resume its original position and shape.

2. In the easel as defined in claim 1, one of 15 said flanges being of a configuration to form slots to receive said studs.

3. In a unit forming a photographic easel, a single base having a paper-supporting top, and sides, more than one paper-holding apertured 20 frame, at least two studs spacedly projecting from one of said sides, said studs being arranged in a straight line and being threaded at their free ends, and matingly threaded nuts to fit the stud threads, each frame being made of resilient 25 material and being shaped to hold a different size of paper, each frame being provided with abutments on two adjacent sides for properly locating the paper to be held, and being placed over the base to fit around the studs for being releasably tightened to the base by means of said nuts, the resilience of the frame material urging the frame secured to the base, upon its bending about a line parallel to said line, to resume its 30 original position and shape.

35 BENJAMIN B. MAHLER.
